POWER UNIT

Otto A. Fritz, Melrose, Mass.

Application September 23, 1936, Serial No. 102,212

7 Claims. (Cl. 156—36)

This invention relates to a power unit designed primarily for use in connection with window shade rollers, but it is to be understood that a power unit, in accordance with this invention, is to be employed for driving any object for which it may be found applicable.

The invention aims to provide, in a manner as hereinafter set forth, a power unit for attaching to a tubular member, to form in connection with the latter, a window shade or winding roller driven from the unit; for obtaining a smoother action of a winding roller with respect to the action of window shade or winding rollers now generally used; for preventing a window shade from flying back when released to wind on its roller; capable of being attached to a tubular member of any suitable length to form a winding roller of the desired length for window shades of different widths; for overcoming the necessity of employing pivot pins for the latching dogs or pawls employed in units of the class to which this invention belongs; and for positioning the latching dogs or pawls within and flush with the side faces of the body of a carrier, as well as forming the dogs and carrier with coacting inherent parts to provide for the freely fulcruming of the dogs to and from roller latching position.

The invention further aims to provide, in a manner as hereinafter set forth, a power unit designed primarily for window shade rollers and which is simple in its construction and arrangement, strong, durable, compact, thoroughly efficient in its use, forming a part of and adapted to be connected to the remaining part of a winding roller, readily assembled, and comparatively inexpensive to manufacture.

With the foregoing and other objects in view the invention consists of the novel construction, combination and arrangement of parts as will be more specifically described and are as illustrated in the accompanying drawings wherein is shown embodiments of the invention, but it to be understood that changes, variations and modifications may be resorted to which fall within the scope of the invention as claimed.

In the drawings:

Figure 1 is an elevation of a shade roller having the power unit installed therewith,

Figure 2 is a longitudinal sectional view of the power unit when installed relatively to the shade roller,

Figure 3 is an exploded view in elevation and perspective of the elements of the power unit other than the housing or casing for said unit,

Figure 4 is an elevation of a blank from which

is formed the coupling element for one end of the outer power transmitting spring.

Figure 5 is a longitudinal sectional view of a modified form of power unit in accordance with this invention showing the same installed with respect to the roller.

Figure 6 is an elevation of the elements of the power unit of the modified form shown in Figure 5 with the omission of the housing or casing for the elements.

Figure 7 is an elevation of a shade roller including a power unit in accordance with this invention and provided with means for attaching the shade to the periphery thereof, and

Figure 8 is a fragmentary view in perspective illustrating a window shade and the means on the roller for attaching the shade to the latter.

Figure 9 is a longitudinal sectional view of still another modified form, and

Figure 10 is a disassembled view of the elements of the modified form shown in Figure 9 with the exception of the outer power transmitting spring.

Referring to Figure 1 of the drawings a winding roller is illustrated and formed from a pair of tubular inter-engaging sections 1, 2. The section 1 is of materially less length than section 2 and constitutes the casing or housing of a power unit in accordance with this invention. The section 2 at its outer end is provided with a rotatable pintle 3 for mounting in a bracket not shown. The sections 1, 2 frictionally revolve together and section 1 has a reduced inner end terminal portion 4 forming a peripheral shoulder 5. The end terminal portion 4 extends into the inner end of the section 2. The inner end edge of the latter abuts the shoulder 5. The portion 4 frictionally engages with the inner face of section 2. The section 1 is capable of being detachably connected to a section 2 of any desired length and whereby such arrangement permits window shades of different widths to be attached to the roller.

With reference to Figures 2 and 3, they illustrate a power unit in accordance with this invention and as aforesigned, the section 1 forms the casing or housing for the elements of the said power unit. The reduced end terminal portion 4 of the section 1 is of materially less length than the remaining portion 6 of such section. The reduced terminal portion 4 is inset with respect to the portion 6 of section 1 thereby providing the section 6 at its inner end with an internal shoulder 7. The unit includes a stationary shaft 8 having attached with its outer end a square pintle 9 for mounting in a suitable bracket not shown. The inner end terminal por-

tion 10 of shaft 8 is formed with a diametrically extending groove 12 and a diametrically extending opening 13 disposed at right angles to and intersected by the groove 12. The opening 13 is arranged in proximity to the base wall 15 of the groove 12. The shaft 8 has mounted on its outer end a cylindrical socket forming member 16 consisting of a body part 17 having integral with its outer end 18 the pindle 9. The shaft 8 extends into the inner end of the member 16 and the latter is anchored to shaft 8 by the pin 19 passing through registering openings (Figure 2) disposed diametrically of the body part 17 of member 16 and the shaft 8. The openings in said body part 17 are indicated at 19^a and the opening in shaft 8 at 19^b. The pin 19 has its ends extend from the outer ends of the openings 19^b for a purpose to be referred to. The body 17 is of circular cross section and is provided between its transverse median and outer end with an outwardly directed annular flange 20. The body 17 outwardly adjacent the flange 20 is formed in its periphery with a pair of diametrically opposed depressions 21, 22. The depressions 21, 22 are positioned in proximity to the end 18. It is to be understood that the shaft 8 and member 16 may be set up from a single length of suitable material. That portion of the outer periphery of the body 17 arranged outwardly with respect to the flange 20 constitutes a bearing surface 23.

Mounted on the surface 23 is a carrier 24 in the form of an annulus of greater diameter than the flange 20. The carrier 24 is revolvably mounted on the surface 23 and bears against the flange 20. The body of the carrier 24 is of a desired thickness and is indicated at 25. The inner and outer edges of body 25 are designated 26, 27 respectively. The body 25 is formed with a pair of diametrically opposed and oppositely disposed cutouts 28, 29 of like form and which open at the inner edge 26 of body 25. Each of said cutouts consists of a circular portion 30, a segmental wall 31 arranged eccentrically to the edge 27, an inclined wall 32, and an inclined wall 33. The circular portion 30 is arranged at one end of the wall 32 and the latter merges into the inner end of said circular portion and into the edge 26. The walls 32, 33 are oppositely outwardly inclined. The wall 33 merges at one end into the edge 26 and at its other end into one end of the wall 31. The wall 31 at its other end merges into the outer end of a circular portion 30. The circular portions 30 of the said cutouts constitute fulcrums.

Mounted in the cutouts 28, 29 are a pair of oppositely disposed latching dogs or pawls of like contour and which operate through the openings 34 provided by the cutouts. The dogs are of less thickness than that of the body of the carrier 24. Each dog consists of a circular end portion 35, a shank 36 which is integral at one end with the end portion 35 and is formed adjacent its other end with a substantially triangular-shaped nose 37^a. That end of the shank of the dog which is integral with the end portion 35 of the dog is eccentrically disposed with respect to such portion 35. The end portions 35 of the dogs are mounted in the circular portions 30 of the cutouts and the said portions 35 are capable of shifting in the portions 30. The side faces of the dogs are flush with the side faces of the body 25 of the carrier 24. On the revolving of the carrier 24 the noses of the dogs ride on the bearing surface 23. The noses of the dogs are capable of engaging with the depressions 21 and 22 for latching the

carrier 24 from movement. The noses of the dogs are diametrically disposed with respect to the carrier 24.

Encompassing the carrier 24 and bodily moving therewith is an annular coupling member 37 formed of an outer end part 38, an inwardly extending intermediate part 39, a rearwardly extending part 40 and inwardly extending inner parts 41. Formed integral with the part 40 at diametrically opposite points of the latter and between the ends of the parts 41 is a pair of rearwardly extending parallel arms 42, 43 of like form and each has its end terminal portion formed with a plurality of slits. The portions of the material freed by the slits in the arm 42 or 43 are oppositely disposed as indicated at 44, 45 to provide a coupler of split loop-like form at the rear end of the arm. The part 38 is positioned against the edge 27 of the carrier 24; the part 39 is positioned against the inner face of the carrier 24; the part 40 is positioned against the edge of the flange 20; the part 41 is positioned against the rear face of the flange 20 and seats on the body 17.

Mounted within the section 1 at the outer end thereof, suitably connected therewith for the purpose of revolving therewith, bearing against the outer face of carrier 24, seated on the part 38 of member 37 and engaging the rear face of the part 39 of member 37 is a combined coupling and cap member 46. The member 46 has an axial opening 47 for the passage of the pindle 9 and an inturned flange 47^a at its inner end. The member 46 couples carrier 24 and member 37 together. The member 46, carrier 24 and member 37 bodily revolve together with the section 1 which constitutes the housing or casing of the elements of the unit.

The unit shown in Figures 1 to 4 includes an inner and an outer power transmitting spring indicated at 48, 49 respectively. The springs are wound in a like direction to increase the tension thereof and expand in a like direction when winding the roller.

The spring 48 encompasses shaft 8. Mounted on the rear portion of the body 17 of member 16 and extending rearwardly from the latter is a sleeve 50 which surrounds the spring 48. The sleeve at its outer end abuts the parts 41 of the member 37 and at its rear end abuts a washer 51 mounted on shaft 8. The sleeve 50 in proximity to its forward end is formed with a pair of diametrically opposed openings 50^a which register with the openings 19^a and receive the extended ends of the pin 19 (Figure 2) whereby the shaft 8, member 16 and sleeve 50 are coupled together. Extending through the opening 13 of shaft 8 is a pin 52 which prevents the rearward movement of the washer 51. The rear end of the spring 48 is extended through the groove 12 whereby shaft 8 and said springs are connected together. The sleeve 50 at its forward end is slotted for a length greater than that portion of body 17 on which sleeve 50 is mounted. The material freed by the slits in the forward end of sleeve 50 provides a resilient tongue 54 formed adjacent member 16 with a transverse inset part 55 through which passes the forward end terminal portion of the spring 48 whereby the tongue in connection with the inner face of sleeve 50 provides for connecting spring 48 and sleeve 50 together. Spring 49 encompasses sleeve 50 and has its rear end extending through a slit 56 and an opening 57 formed in the sleeve 50 whereby the latter and spring 49 are connected together. The forward end of the spring 49 is

passed through the couplers formed on the free ends of the arms 42 whereby spring 48 and member 37 are connected together.

The mounting of the springs 48, 49 in a manner as stated provides for the winding together in one direction and the unwinding or expansion thereof in the opposite direction.

With reference to Figure 4, it discloses a blank indicated at 58 from which member 37 is formed. The blank 58 is of cap-like form provided with a pair of oppositely disposed, segmental-shaped cutouts 59, a pair of slits 60, a pair of slits 61, a slit 63 and another pair of slits 64. The material freed by the slits 60, 61, 62 and cutouts 59 is bent outwardly to provide the arms 42 of the member 37. The material freed by the slits 63, 64 is bent in a manner as indicated at 44, 45 (Figure 2) to provide the couplers for the outer end of spring 49. The pair of slits 60, the pair of slits 61 and the cutouts 59 coact to provide as a part of the blank a pair of oppositely disposed segmental portions 64^a, 64^b arranged in endwise spaced relation and which constitute the parts 41 of member 37.

With reference to Figures 5 and 6, they illustrate a modified form of a power unit in which a single power transmitting spring is employed. The power unit shown in Figures 5 and 6 is generally indicated at 64 and it does not include a spring 49, the sleeve 50, the washer 51 and pin 52. The stationary shaft of the unit 64 is indicated at 65 and is of the same form as the shaft 8 with this exception, that shaft 65 is not provided with an opening 13. The power transmitting spring of the unit 64 is indicated at 69 which has its rear end extending through groove 69^a in shaft 65 whereby the latter and spring 69 are connected together. The forward end of the spring 69 is coupled to the arms 42 of the member 37. Otherwise than that as stated, the form shown in Figures 5 and 6 will be the same as that shown in Figures 1 to 4.

With reference to Figures 7 and 8, the sections of the shade or winding roller are indicated at 70, 71. Section 70 corresponds to section 1 of the power unit. Section 71 corresponds to section 2 referred to. Section 70 is provided with a pair of spaced fastener members 72 for attaching the shade 73 thereto. The section 71 is provided with two spaced pairs of fastener members 74 for attaching shade 73 thereto. The fastener members are of like construction and are provided from inherent parts of the sections 70, 71. The said sections 70, 71 are slotted and the material freed by each slit forms a fastener member. Each fastener member comprises a body part 75 formed with a bendable barb 76. Shade 73 is inserted under the body 75 of the fastener members and the barbs 76 are bent in a manner to extend through the shade 73. The fastener members are then pressed inwardly not only to bind but to connect the shade 73 with the shade or winding roller.

With reference to Figure 3, there is shown interengaging means to provide for the bodily revolving of the carrier 24, coupler member 37 and cap member 46. The said means consists of a pair of edge grooves 77 in the carrier 24, a pair of inset portions 78 on member 37 which engage in the grooves 77 and a pair of inset portions 79 on member 46 which engage in grooves 78 formed in member 37.

With reference to Figures 9 and 10, they include a pair of tubular interengaging sections

80, 81 of the same construction and arrangement as the tubular sections 1, 2.

The power transmitting unit shown in Figures 9 and 10 includes a stationary shaft 82 formed with a reduced outer end terminal portion 83, a socket 84 in the latter, an opening 85 intersecting the socket, a shoulder 86 at the inner end of portion 83, a groove 87 lengthwise thereof at its inner end and an opening 88 intersecting the groove. Encompassing the shaft 82 is an inner power transmitting spring 89 having the inner end terminal portion 90 thereof bent to extend through the groove 87 whereby one end of spring 89 is anchored to shaft 82. Positioned on the latter in proximity to its inner end is a washer 91 which is retained on the shaft 82 by a pin 92 extending through opening 88.

The power transmitting unit shown in Figures 9 and 10 includes a revoluble coupling member 93, stationary washers 94, 95 preferably of fibrous material, a stationary head member 96, a stationary pintle forming member 97, a revoluble carrier 98, a pair of oppositely disposed pawls or dogs 99, 100, a revoluble cap member 101, a securing pin 100^a, a sleeve 102 and an outer power transmitting spring 103 which encompasses the sleeve 102. The latter surrounds the spring 89.

The coupling member 93 consists of an annulus 103^a formed at diametrically opposed points of its outer edge with a pair of rearwardly extending oppositely disposed arms 104, 105 provided at their rear ends with outwardly directed flanges 106, 107 respectively. The annulus 103^a is also provided at diametrical points on its outer edge with forwardly directed segmental shaped oppositely disposed flanges 108, 109, each arranged between the arms 104, 105 respectively. Each forwardly directed flange extends from one side edge of the arm 104 to one side edge of the arm 105. The flanges 108, 109 are transversely grooved, as at 110 in their outer side faces.

The head member 96 comprises a tubular body part 111 formed with a closure 112 at its outer end provided with an axial opening 113. The inner portion of the body part 111 has pairs of lengthwise slits 114 terminating at one end at the inner edge 115 thereof. The material freed by the slits 114 is bent outwardly substantially at right angles to the non-slotted portion 50 of body part 111 and provides a series of spaced radially disposed wings 116. The non-slotted portion of body part 111 outwardly adjacent the wings 116 is formed with a pair of diametrically opposed openings 117, 118.

The pintle forming member 97 comprises a rectangular head 119 having extending rearwardly therefrom a tapered shank 120 formed with an opening 121. The shank 120 at its forward end is integral with the rear end of head 119. The forward end of shank 120 is arranged inwardly of the side faces of head 119 thereby providing a shoulder 122.

The carrier 98 is in the form of an annulus 123 of the desired thickness and constructed in the same manner as the carrier 24. The pawls or dogs 99, 100 are constructed in the same manner as the pawls 36, 37. The pawls 99, 100 are arranged in the annulus 123 in the same manner as the pawls 36, 37 are arranged in the carrier 24 and for the same purpose as pawls 36, 37. The outer edge of annulus 123 is formed with a pair of diametrically opposed grooves 124.

The cap member 101 is arranged relative to section 80 in the same manner as cap member 75

46 is arranged relative to section 1. The cap member 101 is similar in construction to that of cap member 46. The inwardly opposed extending diametrically opposed protuberances or inset 5 parts on the rim of the flange of cap member 101 are indicated at 124^a and they function for the same purpose as the parts 79 of cap member 46. The cap member 101 is suitably secured to and within section 80.

10 The sleeve 102 adjacent its forward end has an opening 125 into which extends the outer terminal portion 126 of spring 89. By the arrangement aforesaid of the spring 89 relative to shaft 82 and sleeve 102, the rear terminal portion 90 15 of spring 89 is anchored to shaft 82 and its forward terminal portion 126 to sleeve 102. The rear end of the latter is slotted diametrically at opposite points, as at 127, 128 and the material freed by the slits outset to form a pair of latching arms 130, 131 for the rear end terminal portion 20 132 of the spring 103. The forward end terminal portion 132 of the spring 103 extends around the arms 104, 105 and is extended into an opening 133 in arm 104 whereby the coupling member 93 and spring 103 are connected together.

When the unit shown in Figures 9 and 10 is set up, the coupling member 93 is arranged on the head member 96 rearwardly of the wings 116. 30 Interposed between member 93 and the wings 116 is the washer 94. The forward end portion of sleeve 102 is mounted upon the rear portion of head member 96 and abuts the annulus 103^a of member 93. The washer 95 is arranged on member 96 forwardly of wings 116. The reduced part 83 of shaft 82 extends into member 96. The shoulders 86 abut the inner ends of a pair of wings 116. The carrier 98 with the pawls 99, 100 arranged therein is mounted on member 96 40 outwardly relative to washer 95. The member 93 is arranged on member 96 outwardly relative to carrier 98 and encompasses carrier 98 and flanges 108, 109 of member 93, as well as overlapping the outer edge of the body part 111 of member 93. 45 The shank 120 of member 97 is extended through members 96, 101 into the socket 84 of shaft 22. The shoulder 122 of member 97 abuts the end 112 of member 96. The shank 120 is anchored to shaft 82 by pin 100^a mounted in openings 85, 121. 50 When the unit is assembled the parts 124^a of cap member 101 are seated both in the grooves 110 of member 93 and the grooves 124 of carrier 98 whereby member 93, carrier 98 and member 101 will bodily revolve in unison about member 96. 55 It is to be understood that other suitable means may be employed for bodily revolving the members 93, 101 and carrier 98. The pawls or dogs 99, 100 coat with the openings 117, 118 in member 96 for latching the unit when occasion requires.

What I claim is:

1. In a power unit for the purpose set forth, a stationary shaft element including a squared pintle at one end, an annular flange in proximity to the inner end of the pintle and a circular part between the pintle and the flange, said part being of less diameter than that of the flange and having its periphery formed with diametrically disposed depressions, a structure surrounding said shaft and revoluble in opposite directions relative to said shaft and including a carrier in the form of an annulus encompassing said part of said element and a pair of oppositely disposed dogs for engaging in said depressions for latching said structure from movement, said dogs be-

ing housed by said carrier, said carrier and dogs having inherent coacting parts to provide for the fulcruming of the dogs in and on the carrier, and a spring means connected with said shaft and structure to provide for the revolving of the latter in one direction when the dogs are free of latching position, said dogs when in non-latching position and during the revolving of said structure riding on the periphery of said part of said element between said depressions. 10

2. In a power unit for the purpose set forth, a revoluble cylinder adapted to form one of the sections of the body of a shade roller, a stationary shaft element mounted in said cylinder, a structure revoluble about the outer end of said element connected to and bodily moving with said cylinder, an inner power transmitting spring encompassing said element and connected to the inner end of the latter, a sleeve encompassing said spring, said sleeve having means for connecting the outer end of said sleeve thereto, an outer power transmitting spring encompassing said sleeve, said sleeve having its inner end provided with means for connecting one end of said outer spring, said structure including means for connecting the outer end of said outer spring thereto, and said structure including oppositely disposed dogs fulcruming therein and engageable in said element for latching said structure from movement. 30

3. In a power unit a revoluble cylinder, a stationary shaft arranged within said cylinder, an inner power transmitting spring encompassing and having its inner end connected to said shaft, a socket forming member mounted on and secured to the outer end of said shaft, said member provided intermediate its ends with an annular flange and with peripheral spaced depressions in proximity to and outwardly of said flange, an annulus revoluble about said depressions and formed with a pair of oppositely disposed cutouts opening at the inner edge of the annulus, oppositely disposed latching dogs arranged in said cutouts for engaging in said depressions for latching the cylinder from movement, said cutouts having edge portions, said dogs having means fulcruming on said edge portions, means arranged within and fixed to said cylinder, encompassing said annulus and flange and formed with inwardly extending arms provided on their free ends with couplers, a sleeve mounted on said spring and provided with means for connecting the outer end of said spring thereto, and an outer spring encompassing said sleeve and having its inner end extending through the body of the sleeve for connecting the latter and outer spring together, said outer spring having its outer end extending through said couplers. 40

4. In a power unit a revoluble cylinder, a stationary shaft element mounted therein and extending outwardly therefrom, an annulus revoluble on said element and being formed with a pair of oppositely disposed cutouts opening at the inner edge of the annulus, a coupling member 65 fixed to and surrounding the annulus, revoluble about said element and formed with inwardly extending arms provided with couplers, oppositely disposed dogs arranged within said cutouts, fulcruming on the edge portion of the cutouts and engageable in said element for latching the cylinder from movement, a power transmitting spring within said cylinder and having its outer end anchored to said couplers and its inner end anchored to the inner portion of the shaft ele- 70 75

ment, a cap within and fixed to one end of said cylinder for revolving the latter, said cap being revoluble on the shaft element, said member having a part encompassing said annulus, said cap encompassing said part, and said cap, part and annulus having coacting interengaging means for connecting them together for bodily revolving in unison.

5. In a power unit a revoluble cylinder, a stationary shaft element arranged within the cylinder, an inner power transmitting spring encompassing said shaft and having its inner end anchored to the inner end of the shaft, a sleeve mounted on said spring, said spring having its outer end anchored to said sleeve, an annulus revolubly mounted on said element being formed with a pair of oppositely disposed cutout portions opening at its inner edge, a coupling member encompassing and fixed to the annulus and revoluble 10 about said element being formed with inwardly extending arms provided with couplers, a cap fixedly secured with said cylinder and member, encompassing the latter and concealing the outer face of said annulus, a pair of oppositely disposed 15 dogs arranged in said cutouts and being formed with noses for engagement in said element to arrest the revolving of the cylinder, said dogs having parts co-acting with the edge portions of said cutouts to provide for the dogs fulcruming within 20 the annulus, and an outer transmitting spring binding said sleeve and having its inner end anchored to the body of the sleeve, said outer spring having its outer end extending through said couplers whereby said outer spring is connected with 25 the cylinder.

6. In a power unit, a bodily revoluble structure, a stationary support for the structure, a power transmitting spring for revolving said structure and having one end anchored to said support, said structure revolubly mounted on said support and formed of a cap member including an axially ap-

ertured disc provided at its outer edge with a rearwardly extending annular flange of angle-shape cross section, an annulus positioned against the inner face of the disc formed with a pair of oppositely disposed cutout openings at the inner edge 5 thereof, said flange being disposed in overlapping relation with respect to the outer edge of the annulus, a coupling member having a part interposed between said flange and annulus, said member abutting the rear face of the annulus and including rearwardly extending arms formed with couplers for connecting thereto the other end of said spring a pair of oppositely disposed latching dogs mounted in said cutouts for engaging into said support to latch the said structure from 10 movement, said dogs and the walls of the cutouts having coacting means to provide for the dogs fulcruming on parts of said walls, and said part, flange and outer edge of the annulus having co-acting means for connecting them together. 15

7. In a power unit, a power transmitting means for operating a revoluble element, said means including a revoluble coupling member, inner and outer concentrically arranged power springs, a sleeve interposed between said springs, a revoluble latching member for said coupling element, a revoluble cap member fixed to and for revolving said element, a stationary supporting structure common to said members, sleeve and springs and upon which said members revolve, said inner 20 spring having one end connected to said structure and its other end to said sleeve, said outer spring having one end connected to said sleeve and its other connected to said coupling member, said outer spring having coil thereof extending 25 through the body of said sleeve, said latching member and structure having coacting parts for latching said coupling member, the said members having coacting interengaging parts to provide for the bodily revolving thereof in unison. 30

40 OTTO A. FRITZ.
